UNITED STATES PATENT OFFICE.

ANGELO CASTELLANI, OF CHICAGO, ILLINOIS.

DESIGN FOR A BRICK.

Application filed September 23, 1922. Serial No. 3,803. Term of patent 14 years.

To all whom it may concern:

Be it known that I, ANGELO CASTELLANI, a former subject of the King of Italy, who has declared his intention of becoming a citizen of the United States, residing at Chicago, in the county of Cook and State of Illinois, have invented a new, original, and ornamental Design for Bricks, of which the following is a specification, reference being had to the accompanying drawing, forming a part thereof.

In the drawing the figure is a perspective view of a brick showing my new design.

I claim:

The ornamental design for a brick, as shown.

In witness whereof, I have hereunto subscribed my name.

ANGELO CASTELLANI.
